UNITED STATES PATENT OFFICE.

WILLIAM S. CAMPBELL OF NEW KENSINGTON, PENNSYLVANIA.

ELEVATOR LOCK.

1,417,451.

Specification of Letters Patent. Patented May 23, 1922.

Application filed December 22, 1920. Serial No. 438,532.

To all whom it may concern:

Be it known that I, WILLIAM SCOTT CAMPBELL, a citizen of the United States, and a resident of New Kensington, in the county 5 of Westmoreland and State of Pennsylvania, have invented certain new and useful Improvements in Elevator Locks, of which the following is a specification.

My invention relates to improvements in 10 elevator locks, usable on either passenger or freight elevators, and it consists in the constructions, combinations and mode of operation herein described and claimed.

One of the foremost objects of the invention 15 is to provide instrumentalities especially adapted to passenger elevators wherein there are usually found lattice-doors on the elevators themselves and other doors in the shaft opening, these instrumentalities including means whereby both doors can be 20 opened substantially at the same time, by manipulation of the operator in the car.

Another object of the invention is to provide 25 an elevator lock arranged to prevent the opening of an elevator shaft-door from the outside, the lock of said door being controlled by the operator from the inside of the elevator.

Other objects and advantages will appear 30 in the following specification, reference being had to the accompanying drawing, in which:

Figure 1 is a side elevation of a passenger elevator, illustrating the application of the 35 improved lock and door opening device.

Figure 2 is a detail horizontal section on the line 2-2 of Figure 1,

Figure 3 is a vertical section on the line 3-3 of Figure 1, the cover plate of the lock 40 being removed and

Figure 4 is a detail elevation of the plate, particularly illustrating a slot, hereinafter described.

This application is a continuation in part 45 of my co-pending application for Letters Patent for elevator locks, filed November 25, 1919, Serial No. 340,447, wherein types of locks for both freight and passenger elevators are disclosed. In order that the 50 reader may understand the purpose of the present lock, attention is directed to Figure 1 wherein is shown a passenger elevator 1 running in the shaft 3. The elevator has a door 2 which is commonly constructed as a 55 collapsible frame consisting of various arrangements of bars pivoted together. It is

unnecessary to describe this door in detail because it is of a well known construction. At the landing 4 there is an outside door 5. According to the present custom, the operator must first open the inside lattice-door 2, then open the outside landing door 4. It is the purpose of the present invention to first provide a lock for the outside door, and means carried by the inside door engageable with a part of that lock for simultaneously undoing the lock of the outside door and opening both doors from the inside of the elevator.

In order that this may be done, namely, 70 that the doors 2 and 5 may be opened simultaneously by one act on the part of the operator, the inside door 2 carries a substantially U-shaped receiver 7. This receiver in riding up or down with the elevator, moves 75 upon the lug 8, projecting inwardly from the bolt 9, and causes the actuation of the bolt in accordance with the movement of the door 2.

Consider Figures 2 and 3. The lug 8 projects out of the slot 10 of the casing 11 which houses the bolt 9 and latch 12. The bolt 9 moves in suitable keepers 13, and has a head 14 engaging the latch projection 15 on one side. A spring 16 engages the projection on the other side.

The latch 12 is pivoted at 17 and has a head 18 arranged to enter the recess of the keeper 19 in the door jamb. So far the operation should be clear. As the elevator approaches the 90 landing from above or below, the receiver 7 rides over the lug 8, and when the inside door 2 is opened, the bolt 9 is first drawn over toward the right, causing the lifting of the latch 12 by reason of the engagement 14 and 15, and on the continued opening movement of the door 2, the outside door 5 is drawn along with it so as to open the landing 4.

While the construction and arrangement 100 of the improved elevator lock and door opening device as herein described and claimed, is that of a generally preferred form, obviously modifications and changes may be made without departing from the spirit of 105 the invention or the scope of the claims.

I claim:

1. In a device as described, a shaft-door, means for locking said door, including a pivoted latch with an extension; means by 110 which the latch is actuated, in engagement with the extension, said actuating means

having a projection; an elevator door and means on said door, engageable with said projection when the elevator reaches the shaft door, enabling the concomitant operation of the latch and opening of both doors.

2. Means for locking a shaft door, comprising a casing carried by the shaft door, with a pivoted latch adapted to come into locking engagement with a jamb; adjacent actuating means mounted in the casing engaging a part of the latch and having a projection through a slot in the casing; and means on an elevator door, engageable with the projection when the elevator reaches

the shaft door, enabling the concomitant opening of both doors, the initial movement of the elevator door raising the latch from locking engagement through said actuating means.

3. An elevator lock, comprising a casing, a latch pivoted in the casing, with an extension housed thereby, a bolt having a head contacting the extension, bearing means slidably supporting the bolt, means on the bolt maintaining the head and extension in engagement, and a lug on the bolt, engageable to shift the bolt and rock the latch.

WILLIAM S. CAMPBELL.
